UNITED STATES PATENT OFFICE

156,344

DUTCH OVEN

Floyd C. Jewell, Long Beach, Calif., assignor, by
mesne assignments, to Crown Jewel Ware, Inc.,
Dallas, Tex., a corporation of Delaware

Application August 15, 1947, Serial No. 140,902

Term of patent 14 years

(Cl. D44—1)

To all whom it may concern:

Be it known that I, Floyd C. Jewell, a citizen of the United States and residing at Long Beach, in the county of Los Angeles, State of California, have invented a new, original, and ornamental Design for a Dutch Oven, of which the following is a specification, reference being had to the accompanying drawing, forming part thereof, in which:

Fig. 1 is a top plan view of a dutch oven, showing my new design,

Fig. 2 is a side elevation thereof, and

Fig. 3 is an elevational view of the dutch oven taken at right angles to Fig. 2 with the lid turned to show the face of the lid knob which is in line with the handles on the sides of the oven.

The dominant features of the present design reside in the knob and handles in conjunction with the dutch oven as shown.

I claim:

The ornamental design for a dutch oven, substantially as shown and described.

FLOYD C. JEWELL.
